APPARATUS FOR HANDLING ORE AND THE LIKE

Original Filed Oct. 10, 1921 2 Sheets-Sheet 2

FIG. 4

INVENTOR;
Charles. E. Davis
BY: Clarence F. Poole
ATTORNEY

UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING ORE AND THE LIKE.

Application filed October 10, 1921, Serial No. 506,712. Renewed June 5, 1924.

To all whom it may concern:

Be it known that I, CHARLES E. DAVIS, a citizen of the United States, residing at Chicago, in the county of Cook and State 5 of Illinois, have invented an Improvement in Apparatus for Handling Ore and the like, of which the following is a specification.

This invention relates to improvements 10 in apparatus for handling ore and the like and has for its principal object to provide an improved apparatus for transporting loose material from one place to another as for instance in a mine.

15 In two prior applications for U. S. Letters Patent, bearing Serial No. 382,696, filed May 20, 1920, now Patent 1,462,688, July 24, 1923, and Serial No. 460,865, filed April 13, 1921, now Patent 1,464,522, Aug. 14, 1923, I have disclosed devices of the class 20 above described comprising a scraper and a movable frame adapted to form a support about which said scraper is guided.

In the present application, I utilize the 25 same general principles of construction and operation as described in the above-mentioned applications, but provide means co-acting with the scraper for automatically advancing the guiding frame toward 30 the material to be transported, as will hereinafter more fully appear. My invention may best be understood by reference to the accompanying drawings, in which Figure 1 is a top plan view of a guiding frame constructed in accordance with my 35 invention.

Fig. 2 is a side view of the frame shown in Fig. 1.

Fig. 3 is a top plan view showing the 40 apparatus in working position in a mine.

Fig. 4 is a side view of the apparatus shown in Fig. 3.

Figs. 5 and 6 are detail views of the 45 ratchet mechanism for automatically advancing the frame.

In the embodiment of my invention illustrated, the apparatus is adapted for use in mining operations in which loose material is to be transported from the working face or place from which the material 50 is being mined, to a place where it may be loaded on mine cars, and comprises a scraper I adapted to be moved on the mine bottom by means of flexible draft cables

2 and 3, and about a guiding frame 4 fixed 55 on the mine bottom in position to form a bearing for one side of the scraper as the latter is advanced into the loose material. The frame 4 is held in place by means of a guiding device such as a pair of mine 60 jacks 5 and 5^a of the usual type which are inserted in a longitudinally disposed slot 6 formed in the frame. The jacks 5 and 5^a are spaced apart so as to guide the movement of the frame in a longitudinal direction. 65

The frame 4 comprises an arcuate shield or bearing member 12, a pair of longitudinally disposed beams 13, 13, a rear end member 14, and suitable side frame members 15 and 16 connecting the shield 12 with the rear end member 14. The longitudinally disposed beams 13, 13, form the slot 6 in which the guide members 5 and 5^a are retained. The forward or bearing 70 face of the shield 12 is curved in a horizontal plane as shown in the drawings, and is provided with a centrally disposed recess or groove 17 extending around the face thereof, a substantially vertical bearing surface 18 above said recess, and an outwardly and downwardly extending bearing surface 19 below said recess. The arrangement of the recess 17 and bearing 75 surfaces 18 and 19 is clearly shown in cross-section in Fig. 2. A plurality of sheaves 20, 20, are mounted about the shield and having their peripheries extending into the recess 17. The arrangement is such that the draft ropes 2 and 3 80 are adapted to engage within the recess 17 and bear on the sheaves 20, 20. In case the draft ropes are allowed to slacken and fall to the ground, they will automatically 85 be moved upwardly along the inclined face 19 and into the recess 17, as soon as tension is applied to the ropes during the 90 operation of the apparatus.

The scraper 1 is preferably of the bottomless type. The specific construction of 100 scraper illustrated herewith forms the subject-matter of a separate application filed by me October 10, 1921, Serial No. 506,711, and is provided with an inner side 1^a having a plurality of anti-friction bearing 105 members 1^b adapted to engage the head frame above and below the recess 17 as indicated in dotted lines in Fig. 2. Other

suitable forms of scraper may be used if desired.

Referring now to the means for automatically advancing the frame 4, I provide a ratchet mechanism 8 preferably mounted on the rear end member 14 of the frame and having suitable connection with the fixed guide members 5 and 5^a for moving the frame longitudinally toward the material to be transported. In the embodiment illustrated, this ratchet mechanism comprises a ratchet wheel 9 carried on a vertically disposed shaft 10 and operatively connected to a winding drum 11. A draft rope 11^a is wound on the drum 11 and has its forward end connected to one of the guiding jacks such as the forward jack 5, as shown in Figs. 3 and 4. The ratchet wheel 9 is operated by an arm 21 extending laterally from the frame at a point intermediate the forward shield 12 and the rear end member 14. Said arm is pivotally connected to one of the main frame members 13 by means of a bolt 22 mounted on said frame and passing thru an arcuate slot 23 formed in the inner end of said arm. The purpose of this slot will be hereinafter described. A connecting bar 24 is pivotally attached to the arm 21, and extends rearwardly to a rocking arm 25 pivotally journaled on the shaft 10 and carrying thereon a dog 26 adapted to engage the ratchet wheel 9. A second dog 27 is mounted on the frame to prevent rotation of the ratchet wheel 9 while the operating dog 26 is disengaged from said ratchet wheel. Said dogs may be maintained in operative engagement with the ratchet wheel by any suitable means, such as pivoted latches 28, 28^a, (see Figs. 5 and 6) adapted to engage a lug 28^a on each of said dogs and held in place by gravity. The said dogs may be released when desired by rocking the latches on their axes, as shown in dotted lines in Fig. 6.

Means for maintaining the arm 21 forwardly in operative position comprises a weighted crank arm 30 pivotally mounted on a suitable support 31 on the interior of the shield 12. Said crank arm 30 is connected to the arm 21 by a tie-bar 32 having pivotal engagement on the arm 21 intermediate the bar 24 and the bearing bolt 22 forming the main pivotal connection of said arm. A suitable stop 33 is mounted on the rear end of the scraper 1 to engage the outer end of arm 21 as the scraper is moved rearwardly about the head frame 4 as indicated in Fig. 3.

Means are also provided for actuating the ratchet mechanism 8 by hand, which comprises a vertically movable pivoted arm 35 having a downwardly extending latch member 36 adapted to engage a notched wheel 37 carried on the winding drum shaft

10. The arm 35 is adapted to be manually operated by a handle 38 which is moved upwardly to bring the latch 36 into engagement with the notched wheel 37 and operate the winding drum 11 independently of the automatic actuating mechanism above described.

The operation of the device above described is as follows:

The scraper 1 is reciprocably operated by means of the head rope 2 and tail rope 3, and gathers its load while being moved forwardly about the guiding frame 4, and transports its load to a suitable loading chute or the like, at a distance from the frame. As each load is gathered, the pile of material is diminished, so that it is necessary to advance the frame 4 longitudinally from time to time. This is accomplished by moving the scraper rearwardly about the frame 4 to bring stop 33 thereon into engagement with the arm 21, connected with the ratchet mechanism 8. Continued pull on the tail rope 3 swings said arm rearwardly, fulcrumed on bolt 22, and rotates the rocking arm 25 and dog 26 carried thereby, to actuate ratchet wheel 9 and the winding drum 11. A portion of cable 11^a is thus wound in, and being connected to the fixed jack 5, the frame is moved forwardly along the ground, as indicated in dotted lines in Fig. 3. As soon as the scraper is moved forwardly, the weighted arm 30 actuated by gravity serves to return the operating arm 21 and rocking arm 25 connected therewith into its initial operating position. By means of this arrangement the frame is brought nearer the material to be gathered. It is often undesirable to advance the frame every time the scraper is loaded, and in such case, the scraper may be stopped before it comes into engagement with the operating arm 21.

The purpose of the curved slot 23 on the inner end of arm 21 is to allow said arm to be swung out of the path of the scraper when desired. As already described, the tie-bar 32 associated with weighted arm 30 is pivotally connected to the operating arm 21 intermediate the bearing bolt 22 and bar 24 associated with the ratchet mechanism. With the arrangement described, the outer end of the arm 21 may be swung forwardly from its normal position shown in Fig. 1 with said arm fulcrumed on bar 24. The curved slot 23 is designed so as to permit the inner end of the operating arm to swing rearwardly a sufficient distance to allow said arm to be moved out of the path of the scraper. This feature is advantageous when the scraper is accidentally moved rearwardly beyond the operating arm, in which event it may readily pass said arm on its forward movement. Although I have shown and described

one form in which my invention may be embodied, it will be understood that many other means may be employed for accomplishing the same results without departing from the spirit and scope of my invention.

5 I do not therefore wish to be understood as limiting myself to the specific construction illustrated herein excepting as specifically limited in the appended claims.

10 I claim as my invention:

1. In an apparatus of the class described, a frame adapted to be fixed against lateral movement, and having a curved lateral bearing portion provided with a horizontally dis-

15 posed groove, and an outwardly and downwardly inclined bearing surface below said recess.

2. In an apparatus of the class described, a frame adapted to be fixed against lateral movement, and having a curved lateral bearing portion provided with a horizontally dis-

20 posed groove, and a plurality of sheaves having their peripheries extending into said recess.

25 3. In an apparatus of the class described, a frame adapted to be fixed against lateral movement, and having a curved lateral bearing portion provided with a horizontally disposed groove, a plurality of sheaves hav-

30 ing their peripheries extending into said recess, and an outwardly and downwardly inclined bearing surface below said recess.

4. In an apparatus of the class described, a frame having a lateral bearing portion, a support for said frame adapted to be fixed against lateral movement, a reciprocably-operated conveyor device including a scraper, and means on said frame coacting with said conveyor device for moving said frame

40 with respect to its support.

5. In an apparatus of the class described, an elongated frame having a curved forward portion, a support for said frame adapted to be fixed against lateral movement, a reciprocably-operated conveyor device including a scraper adapted to have lateral engagement with said curved portion, an actuating mem-

ber extending laterally beyond said frame in position to be engaged by a stop carried by said conveyor device and means associated with said actuating member for advancing said frame longitudinally with respect to its support.

6. In an apparatus of the class described, a frame, a support for said frame adapted to be fixed against lateral movement, a reciprocably-operated scraper, and means on said frame co-acting with said scraper for moving said frame with respect to its support.

7. In an apparatus of the class described, a frame having a lateral bearing portion, a support for said frame adapted to be fixed against lateral movement, a reciprocably-operated conveyor device including a scraper, means on said frame co-acting with said conveyor device for moving said frame with respect to its support comprising a pivoted arm, and ratchet mechanism connected with said arm, having means operatively connecting said ratchet mechanism with said sup-

port.

8. In a device of the class described, an elongated frame having a curved forward portion, a support adapted to be fixed against lateral movement, a conveyor device including a scraper adapted to have lateral engagement with said frame, means co-acting with said conveyor device for moving said frame longitudinally with respect to its sup-

port, said means comprising an arm normally extending laterally from said frame into the path of movement of said scraper, ratchet mechanism adapted to be actuated by rearward movement of said arm from its normal position, and means permitting forward movement of said arm from its normal position whereby it may be moved out of the path of movement of the scraper.

Signed at Chicago, in the county of Cook and State of Illinois, this seventh day of October, 1921.

CHARLES E. DAVIS.
